UNITED STATES PATENT OFFICE.

MARIA RODRIGUES LOIJA, OF GEORGETOWN, BRITISH GUIANA.

ELECTRICALLY-PROPELLED BOAT.

1,355,156.

Specification of Letters Patent.

Patented Oct. 12, 1920.

Application filed August 19, 1919. Serial No. 318,595.

To all whom it may concern:

Be it known that I, MARIA RODRIGUES LOIJA, a citizen of British Guiana, residing at 8 Brickdam, Georgetown, in the county of 5 Demerara, State of British Guiana, have invented a new and useful Electrically-Propelled Boat; and I do hereby declare the following to be a full, clear, and exact description of the invention, such as will enable 10 others skilled in the art to which it appertains to make and use the same.

The invention relates to electrically operated boats and has for its object, to provide a boat of this character wherein the 15 power for operating the propelling means of the boat is obtained from a trolley wire located over the course of the boat. Also to provide guide cables located over the stream or creek adapted to be engaged by vertically 20 adjustable members, carried by the ends of the boat, whereby the necessity of providing the boat with steering mechanism is obviated.

A further object is to provide the ends of 25 the boat with vertically adjustable guide cable members, whereby the boat will be guided in its course in a creek or canal, said adjustable members being adjustable so that the ends thereof will be capable of adjustment so that they may be adjusted to 30 guide cables at different heights and also to compensate for the distances from the water at different times, where the canal or creek is fed by tidal waters.

35 A further object is to provide an electrically operated boat, said boat being provided with means for engaging guide means located over the waterway and to provide conductor means whereby the power will be conducted 40 from any suitable source to the motor located on the boat, thence back to the source of power through one of the vertically adjustable guide standards.

With the above and other objects in view 45 the invention resides in the combination and arrangement of parts as hereinafter set forth, shown in the drawings, described and claimed, it being understood that changes in the precise embodiment of the invention 50 may be made, within the scope of what is claimed without departing from the spirit of the invention.

Figure 1 is a perspective view of the boat, showing the same in position under the electric conductor wire and guide cables.

Fig. 2 is a side elevation of the boat, show-

ing the same in position under the guide cables and towing a boat.

Fig. 3 is a view of two of the adjustable guides.

Fig. 4 is a sectional view through one of the adjustable guides.

Fig. 5 is a detail view of the guide elevating gear.

Referring to the drawings the numeral 1 65 designates a boat of conventional form and 2 the deck thereof. The ends of the boat are provided with eyes 3, to which a coupling bar 4 may be attached as at 5, the other end of the coupling bar being attached as at 6 to an eye 7 on one of the ends of a boat 8 that is to be towed. It being understood 70 that any number of boats may be towed as desired.

Secured by means of rivets 10 to the deck 75 2 of the boat are standards 11, which are provided with vertical guide passages 12. Slidably mounted in the guide passages 12 are rack bars 13 which terminate at their upper ends in bifurcations 14. Between the 80 arms 15 of said bifurcation sheaves 16 are pivotally mounted, the sheaves 16 being adapted to engage the guide cables 17 which are suspended over the waterway and are held in position, by means of the usual posts 85 located on the banks of the stream and the usual spanner wires. The standards 11 are provided with brackets 18 and rotatably mounted in the brackets 18 are the ends of the shafts 19, which shafts have keyed there- 90 on by means of the keys 20 gears 21. Gears 21 mesh with the teeth of the vertical racks 13, so that when it is desired to raise or lower the cable engaging sheaves 16 a revoluble movement of the shafts 19 will cause 95 the racks 13 to move upwardly or downwardly. This revoluble movement is accomplished by the operator grasping the handle members 22 of the shaft and forcing the shaft around. Therefore it will be seen that 100 the guides located at each end of the boat may be raised in unison, so as to adjust the same to guide cables located at different distances above the waterway, also to adjust the guides for different heights of the 105 guide cables from the waterway, which may be caused by the fact that some waterways are fed by tidal waters.

The source of power may be located at any point along the waterway or at a distance from the same. However for purposes of illustration a battery symbol 23 is

used. The current passing from the same over the wire 24 to the conductor wire 25, thence through the trolley 26 to a reversing switch 27, from which switch the current passes to the motor 28 which drives the propeller of the boat, said propeller 29 being capable of being reversed by means of the reversing switch 27. The current after leaving the motor 28 passes through the switch 27, thence over the wire 28^a to one of the vertical racks 13 to one of the guide cables 17 from which it passes to the wire 30 which carries the current back to the source of supply.

15 When it is desired to run the boat on a waterway, the rack bars 13 are forced upwardly by means of the gears 21 when the shafts 19 are revolved. The trolley is then placed in contact with the conductor wire 25. Then the motor is started which revolves the propeller 29, thereby forcing the boat forwardly. However the motor may be reversed by means of the switch 27 when it is desired to move the boat in the other direction. The rack bars 13, the sheaves of which engage the cable guides 17 may be worked upwardly or downwardly to accommodate the sheaves to cables at different heights from the water. This being particularly necessary where the waterway is fed by tidal waters. It will be seen that as the boat advances, that the guide cables will cause the boat to move according to the position of the guide cables.

30 35 Keyed by means of the keys 32 to the shafts 19 are ratchet wheels 33 which are adapted to be engaged by the pawls 34, which are pivoted to the brackets 18 of the

standards. These pawls and ratchets when in engagement hold the rack bars 13 to their 40 adjusted positions, but when released allow the rack bars to come down by force of gravity.

The invention having been set forth what is claimed as new and useful is:—

45 An electrically propelled boat comprising a hull, means for propelling the same, guide cables located over the waterway and adapted to be engaged by vertically adjustable guide members, said guide members comprising hollow standards, said standards at each end of the hull being in transverse alignment, vertically slidable rack bars in said hollow standards, the upper ends of said rack bars being provided with bifurcations 50 adapted to receive the guide cables, transversely disposed shafts rotatably mounted in bearings mounted on the hollow standards at each end of the hull, gears carried by said shafts and meshing with the vertically disposed rack bars, means whereby said transversely disposed shafts may be rotated to move the rack bars upwardly into engagement with the guide cables, and ratchets whereby the rack bars will be held 55 in any position to which they have been moved, or allowed to telescope in the hollow standards under their own weight.

60 In testimony whereof I have signed my name to this specification in the presence of 70 two subscribing witnesses.

MARIA RODRIGUES LOIJA.
